UNITED STATES PATENT OFFICE.

JAMES H. CLARK, OF FLINT, MICHIGAN.

DRAFTING INSTRUMENT.

1,112,264.

Specification of Letters Patent. Patented Sept. 29, 1914.

Application filed November 2, 1911. Serial No. 658,124.

To all whom it may concern:

Be it known that I, JAMES H. CLARK, a citizen of the United States, residing at Flint, in the county of Genesee and State of Michigan, have invented new and useful Improvements in Drafting Instruments, of which the following is a specification.

This invention relates to drafting instruments and more particularly to that type 10 known as dividers.

The object of the invention is provision of a simple and efficient device of this character whereby the points for a true ellipse may be readily obtained or whereby the 15 device may be used as a simple divider.

Further objects of this invention will appear as the following specific description is read in connection with the accompanying drawing, which forms a part of this application, and in which:—

Figure 1 is a side elevation. Fig. 2 is a top plan view. Fig. 3 is an edge elevation. Fig. 4 is a side elevation with the adjustable leg reversed. Fig. 5 is a diagrammatic view illustrating the application of the device.

Referring more particularly to the drawing, 1 represents the ordinary knurled handle of the divider body 1^a from which 20 diverge the spring legs 2 and 3, both of which are provided with an ordinary needle point 4. Intermediate the length of the legs suitable bearings 5 are journaled therein and these bearings are provided with transverse 25 screw threaded apertures adapted to receive the right and left hand screw 6, the right hand portion of the screw being threaded into the bearing of the leg 2, while the left hand portion of the screw is threaded into 30 the bearing of the leg 3. A knurled disk 7 is secured to the screw for operating the same so as to spread or draw the legs together, as desired.

Bearings 5 in each leg are provided with laterally projecting studs which are engaged in the bifurcated lower ends of connecting links 8. The upper ends of each are similarly bifurcated so as to pivotally receive laterally extending studs 9 carried by a parallel bar 10 which is apertured to receive the body 1^a, as shown at 11. Beyond the connection of the left hand link with the bar 10, the bar is squared and slidably mounted thereon is a head 13 of a leg 14 which is provided, as usual, with the point 15. The head 13 is transversely

apertured to receive the squared portion 12 of the bar 10 and is vertically apertured to receive an adjusting screw 16 which acts to clamp the leg upon the arm in adjusted 60 position. It will be noticed that as the legs 2 and 3 are drawn together, the bar 10 will drop upon the body 1^a and the points 4 and 15 will always be maintained approximately collinear.

For setting the instrument, we will assume, for instance, that we have a round bar, as shown in Fig. 5 at 17, and it is desired to obtain an ellipse represented after the bar has been sawed off at the desired 70 angle. Take the radius 18, which is equal to one half of the diameter of the bar, swing a line 19 from the center 20 to a point of intersection with the line representing the form desired, the point of intersection being indicated at 21. The instrument is now set with the point A at the junction of the bottom line of the bar to the diagonal cutting line and the point B is set on the point 21 while the point C of the leg 14 is set 80 upon the point 20. We now have the instrument set so that the distance between the points A and C and the distance between the points B and C are equal to one half of the major and minor axes respectively. In order to obtain the points for a true ellipse, the lines representing the minor and major axes should cross each other at 90°. Then by taking the instrument and keeping the points A and B on the lines 90 representing the minor and major axes respectively, the point C will produce the true location for the points of an ellipse since the distance between the points B and C and A and C are equal to the semi-minor 95 and the semi-major axes of a true ellipse. It will be noticed that the leg 14 is adjustable upon the squared portion of the bar 10 and that it is also reversible to obtain the points for an extremely small ellipse or 100 a larger ellipse than a certain length bar would permit providing the leg was straight thus increasing the range of the instrument.

What is claimed is:

1. A drawing instrument of the class described comprising a body having a handle, a pair of yieldable legs provided on said body and having pointed free ends, means by which said legs may be flexed laterally to effect relative adjustment of the points 105 thereof, a third leg having its free end pointed, means for mounting the last-named

leg movably upon the body, and means associating the said mounting means for the third leg with the first-named legs for maintaining the points of all the legs in substantial collinearity irrespective of the relative adjustment of the first-named legs.

2. A drawing instrument of the class described comprising a body having a handle, a pair of yieldable legs provided on said body and having pointed free ends, means by which said legs may be flexed laterally to effect relative adjustment of the points thereof, a third leg having its free end pointed, a member mounted for longitudinal movement upon the said body for connecting the third leg therewith the said third leg being adapted to be adjusted laterally with respect to the first-named legs, means for securing the third leg in laterally adjusted position upon the said member, and means for maintaining the points of all the legs in substantial collinearity irrespective of the relative adjustment of the first-named legs.

25 3. A drawing instrument of the class described comprising a body having a handle, a pair of yieldable legs provided upon said body and having pointed free ends, means by which said legs may be flexed laterally to effect relative adjustment of the points thereof, a laterally projecting bar mounted upon the body for longitudinal movement thereon, a third leg attached to the said bar and having a pointed free end disposed in substantial collinearity with the points of the first-named blades, and means operatively connecting the first-named legs with the said bar for maintaining the collinearity of the points of all the legs.

40 4. A drawing instrument of the class described comprising a body having a handle, a pair of yieldable legs provided upon said body and having pointed free ends, means by which said legs may be flexed laterally to effect relative adjustment of the points thereof, a laterally projecting bar mounted upon the body for longitudinal movement thereon, a third leg attached to the said bar and having a pointed free end disposed in substantial collinearity with the points of the first-named blades, and a pair of rigid

link members having corresponding ends thereof pivotally connected to the respective first-named legs and their opposite ends pivoted to the said bar at points spaced from each side of the body.

5. A drawing instrument of the class described comprising a body having a handle, a pair of yieldable legs provided upon said body and having pointed free ends, means by which said legs may be flexed laterally to effect relative adjustment of the points thereof, a laterally projecting bar mounted upon the body for longitudinal movement thereon, a third leg attached to the said bar and having a pointed free end disposed in substantial collinearity with the points of the first-named blades, and a pair of rigid link members having corresponding ends thereof pivotally connected to the respective first-named legs and their opposite ends pivoted to the said bar at points spaced from each side of the body, the said link members being movable in a common plane with the said legs and bar.

6. A drawing instrument of the class described comprising a body having a handle, a pair of depending yieldable legs provided upon said body and having pointed free ends, means by which said legs may be flexed laterally to effect relative adjustment of the points thereof, a laterally projecting bar slidably mounted upon said body for longitudinal movement thereon, a third leg slidably mounted upon the said bar and having a pointed free end disposed substantially in collinearity to the points of the first-named legs, means by which the third leg may be secured in its different longitudinally adjusted positions upon the said bar, and means operatively connecting the first-named legs with the bar for maintaining the approximate collinearity of the said points throughout their range of adjustment.

In testimony whereof I affix my signature in presence of two witnesses.

JAMES H. CLARK.
